RANGE

Jesse W. Barker, Geneva, N. Y.

Application May 9, 1936, Serial No. 78,924

2 Claims. (Cl. 126—1)

This invention relates to improvements in combination oil and gas ranges and has for its principal object to provide a flue system which will greatly increase the oven heating capacity and efficiency of the hot air and gases circulating therethrough.

Other objects and advantages of the invention will be understood as the description is considered with the accompanying drawings, in

10 which:

Figure 1 is a top plan view of a stove embodying the invention;

Figure 2 is a front elevation of the stove shown in Figure 1;

15 Figure 3 is a fragmentary view taken on the line 3—3 of Figure 2 illustrating the by-pass for direct exhaust of gases to the flue during initial heating of the oven;

Figure 4 is a partial end elevation;

20 Figure 5 is a section on the line 5—5 of Figure 1; and

Figure 6 is a section on the line 6—6 of Figure 5.

Referring more particularly to the drawings, 25 I denotes a combination oil and gas range comprising front and rear walls 2 and 3, side or end walls 4 and 5 and a top 6. The range is provided with the usual top gas burners 7, four in number, arranged within a burner compartment 8, beneath the burner openings 7' in the top wall 6, grids 9 being seated in these openings. The compartment 8 extends above and is spaced from the top wall 10 of an oven 11, thus forming 30 an upper space between its bottom wall and the top wall of the oven extending across the top of the oven for the passage of the hot air and gases. This space is subdivided into two top passages or ducts 13 and 14 by a vertically disposed partition wall 15. The top burners are 35 controlled by valves 12, and gas is supplied to the burners from a manifold, not shown.

Suitably supported in an oil burner compartment 16 at the left side of the range, viewing Figure 5, are any suitable number of oil burners 17, two being shown. Oil is fed to the burners in any desirable manner from an oil tank 18, supported upon bracket 19, secured to the rear of the range. A protective wall 20 serves as one side wall of passage or duct 14 and also protects the oven end wall against excessive direct heat from the oil burners 17. Drippings from the burners are caught in a tray 27.

An oven gas burner 20' is located beneath the bottom wall of the oven for use in case it is not 45 desirable to use the oil burners, or where addi-

tional heat for the oven is required. This burner is located in a bottom duct 21 formed by the space between the bottom of the oven and the bottom wall 22 of the range 1, and receives gas from a supply pipe 23, connected with a manifold, not shown.

An opening 23, in the rear wall 3 of the range, and positioned directly beneath the top thereof, communicates with the upper end of a back conduit 24, which extends downwardly at an angle along the rear wall 3 and communicates at its lower end with a bottom duct 21. This duct 21 is also in communication with the lower end of a vertically disposed side duct or conduit 25 which in turn communicates at its upper end 15 with the duct or space 13, previously described as occupying the space between the top of the oven and the bottom of top gas burner box or compartment 8. The duct 25 occupies the space between one side wall of the oven and the side 20 wall 4 of the range. Hot gases entering duct 13 from duct 25, escapes through an exit opening 26 formed in the back of the range and leading from the duct or space 13 to a stack or flue 34.

When oil burners 17 are initially lighted a 25 sliding damper 29 normally closing openings 30, in division wall 15 is manually opened by means of a rod 31. This permits the hot expanding gases rising from the oil burner box or compartment 16, to pass from the narrow top duct 30 through openings 30 and across a considerable top area of the oven before escaping to the flue. As a result the top of the oven is quickly heated and this in turn creates a natural draft which causes the gases to flow in a manner about to 35 be described, after the damper 29 has been closed.

Assuming that oil burners 17 are burning and that damper 29 has been closed after the initial operation just described, the hot gases will be 40 drawn downwardly through the duct 24 by the draft previously created. As the hot gases emerge from the lower end of duct 24 into bottom passage or duct 21, extending underneath the oven 11, a baffle plate 32 causes the gases to 45 sweep forwardly in a wide curving course before passing from the duct 21, into the lower end of side duct 25, thus insuring contact with and heating of the entire bottom area of the oven. From the right side of duct 21, the direction of 50 flow is upwardly through duct 25 and thence inwardly through duct 13, where a baffle plate 33 causes the gases to sweep across the top of the oven to and through flue opening 26.

From the foregoing it will be seen that the hot 55

- gases can be passed directly to the flue across a considerable top area of the oven, by opening the damper 29, and that after initially heating the oven and promoting a draft through opening 5 28 to the flue 34, the course of the gas can be changed to flow downwardly through the conduit 24 by the shortest possible route, along the rear of the oven at one side thereof and thence underneath the oven, and finally upwardly along 10 the other side and over the top to the flue. The hottest gases thus reach by the most direct and quickest route, the side of the oven remote from the fire box 16 and the bottom of the oven, the portions to which it is desired to convey the 15 greatest heat. While I have illustrated the conduit 24 as extending downwardly and to one side or in a diagonal direction, in actual practice this conduit is extended straight down the back of the stove.
- 20 The duct 14 in effect constitutes a gas chamber or pocket for heating the top portion of the oven at the oil burner box side of the range after the oven top has been initially heated by passing the hot gasses through the damper 29.
- 25 An important feature of the invention resides in the flue arrangement and in the location of the gas burner 20'. In this connection it will be noted that by running the down draft flue or duct 24 directly down the back of the range, or substantially in that direction, then under the oven, up the back end of the range, then over the back section of top into the outlet flue 34, it is possible to locate the gas burner under the oven in the passage 21, directly at the bottom of the 30 down draft flue or duct 24. This flue 24, in addition to carrying heat from the oil burners to the bottom of the oven, also furnishes the air for the oven gas burner 20'. In prior dual oven range constructions with which we are familiar, 35 the gas burner is located in the oven through a well in the bottom of the oven, the air being furnished through this well. It is also common practice to bring the primary air in through a

tube. This necessitates the use of a baffle plate in the bottom of the oven, whereas according to the present invention, this is unnecessary because ample air is supplied to the gas burner through the flue 24.

Having thus described my invention:

What I claim is:

1. A range comprising a casing, a fire box therein at one end, a heater in said fire box, an oven within the casing and in contact with the fire box at one end, and having a passage across the top, a passage at one end and a passage across the bottom, said passages communicating and forming a continuous passage, the upper passage communicating with the fire box, a damper controlling the communication between the fire box and upper passage, a flue communicating with the upper end of the fire box and extending diagonally downwardly and communicating with the bottom passage adjacent the fire box at one side and the upper passage communicating with a flue approximately midway its ends.

2. A range comprising a casing, a fire box therein at one end, a heater in said fire box, an oven within the casing and in contact at one end with the fire box and having a passage across the top, a passage at one end opposite the fire box and a passage at the bottom forming a continuous passage from the fire box under the bottom and around the end and across the top to 30 and communicating with the fire box, a damper controlling the communication between the upper passage and the fire box, a down flue communicating with the upper end of the fire box and extending diagonally downwardly and communicating with the bottom passage adjacent the fire box, a baffle plate in the bottom passage intermediate its ends to cause a zigzag passage from the down flue to the end passage and a flue connected to the upper passage approximately midway its ends.
